Fig. 3.

FIG. 4.

This technical drawing illustrates a mechanical assembly, likely a component of a larger machine. The drawing is divided into several sections, each labeled with a reference number:

- Top Left Section:** Contains parts labeled 26, 138, 15, 60, 88, 110, 99, 72, 195, 91, 104, 92, 102, 91, 88, 93, 175, 177, 135, 11, 58, 308, 130, 133, 69, 120, 63, 59, 67, 17, 57, 106, 135, 138, 15, 60, 88, 110, 99, 72, 195, 91, 104, 92, 102, 91, 88, 93, 175, 177, 135, 11, 58, 308, 130, 133, 69, 120, 63, 59, 67, 17, 57, 106.
- Top Right Section:** Shows a coil assembly with parts 162, 170, 159, 160, 158, 154, 157, 172, 150, 50, 44, 51, 53, 156, 155, 166, 163.
- Bottom Left Section:** Shows a coil assembly with parts 250, 248, 236, 238, 242, 230, 252, 234, 260, 262, 34, 209, 209, 193, 197, 41, 188, 188, 219, 36, 186, 178, 178, 201, 192, 180.
- Bottom Right Section:** Shows a circular component with a central hole and a slot, labeled 40.

ALARM LOCK

Joseph R. Rodth, New York, N. Y.

Application February 6, 1936, Serial No. 62,610
Renewed January 19, 1939

9 Claims. (Cl. 177—314)

The present invention relates to locks and more particularly to alarm locks, that is locks so constructed that they cause an alarm to sound when subjected to unauthorized tampering.

5 It is a general object of the invention to provide a novel lock of this kind that is particularly suitable for doors to apartments although it will be evident that the use of the invention is not so limited since it can be used under various

10 conditions and for various purposes.

One object of the invention is to provide an alarm lock that makes unauthorized access to homes and the like by any of the methods involving relatively little demolition difficult or

15 impossible without setting off the alarm.

Another object of the invention is to provide such a lock in which both the locking and the alarm mechanisms are protected against unauthorized access and in addition to provide such

20 a lock which, in addition to affording such protection, is of such construction that it can be readily installed by relatively unskilled persons.

A further object of the invention is to provide such a lock which can be so installed without altering the door or other adjacent construction.

Additional objects of the invention, including the special provision against certain of the more common methods of unauthorized entry, will appear from the following detailed description.

In the accompanying drawings there is illustrated a preferred embodiment of the invention, certain details of which may be varied without departing from the invention as defined by the

35 appended claims. In these drawings:

Figure 1 is a front elevation showing a lock comprising the invention attached to a door;

Figure 2 is a transverse, substantially central vertical sectional view through the lock of Figure 1, taken on line 2—2 thereof;

Figure 3 is a horizontal sectional view through the lock of Figure 1, taken on line 3—3 of Figure 5;

Figure 4 is a wiring diagram showing also certain of the mechanical parts associated in the several circuits;

Figure 5 is a longitudinal vertical sectional view through the lock of Figure 1 and taken on the line 5—5 of Figure 3;

Figure 6 is an enlarged detail front view of one of the switches, the view being taken on line 6—6 of Figure 5;

Figure 7 is an enlarged detail bottom view of another switch, this view being taken on line 7—7 of Figure 8;

Figure 8 is a longitudinal sectional view through the same switch taken on line 8—8 of Figure 7;

Figure 9 is a transverse sectional view through the same switch taken on line 9—9 of Figure 7;

Figure 10 is an enlarged detail horizontal sectional view through a portion of the lock housing taken on line 10—10 of Figure 5 and showing the lock bolt operation control cam;

Figure 11 is a longitudinal sectional view through the lock housing taken on line 11—11 of Figure 3;

Figure 12 is a vertical sectional view taken on the line 12—12 of Figure 2, and

Figure 13 is an enlarged horizontal sectional view through one of the switches and taken on line 13—13 of Figure 11.

Referring in detail to the drawings, a metal box-like shell or housing 11 is provided, which is open on one side, this opening being closed by the door surface when the lock is in place, and in its other side has an opening in which there is fitted a lock door 12 and a series of slotted openings 13, behind which a shield plate 10 prevents access through the openings 13 to the alarm and its associated mechanism. Into this shell there is fitted a locking knob 14 which operates the bolt 15, as hereinafter described, independently of the key operation of the lock cylinder, and opposite and independent of the knob is a lock cylinder 30. The bolt 15 has pivoted to it an arm 16, which has an end having a circular opening fitting over the pin 19 on knob arm 20, and having a forked portion opposite the pin 19, for engagement with the pin 37 on cam arm 35 of the lock cylinder. The knob pin 19 moves through 180°, clockwise as viewed in Figure 5, and returns counterclockwise to the position of Figure 5. Lock cylinder pin 37 moves through 360°, and during half its movement moves the bolt 15 by engaging in the forked end of arm 16.

The shell or housing 11 is attached to the door 23 by means of four wood screws 24. The invention includes means hereinafter described for setting the alarm in action if these screws are tampered with when the bolt is in locked position. There is also provided keeper 26, to be attached to the jamb 27. The lock can be operated from the outside by means of a standard lock cylinder 30 which is attached to the door and is free of the lock itself. A flat connecting rod 34 attached to and rotatable with the lock cylinder 30 passes through the slotted opening provided for it in the cam disk 36, car-

rying the arm 35 and eccentrically fixed pin 37, which, when the cylinder 30 is turned, engages the bolt arm 16 and causes the bolt 15 to move back and forth as desired. This locking mechanism is per se not new, and for the purposes of the invention need not be of the specific design shown in the drawings; the invention includes the various devices which comprise the alarm system in combination with the essential elements of such a locking mechanism.

The invention in its entirety thus includes an alarm and means for causing the alarm to be set off when the door is pried, or the lock is pried, cut or otherwise tampered with. The actual alarm may be an electric bell, and in structures carrying out the invention to what is now considered the best advantage, the lock itself forms part of the alarm or bell circuit. In the embodiment here shown as an example, carried inside the housing 11 is an electric bell 40, in itself of ordinary construction, which is attached to the back plate 41 which is fixed to the lock housing by a screw 42 threaded into the guide post 18, and positioned by abutments 38 formed in the housing. The bell is completely insulated from the lock, the current source derived from dry cell batteries 44 attached to the same plate and located within the lock housing, where, without the key hereinafter referred to, they cannot be reached without setting off the alarm. As shown in Figure 4, from one terminal of the batteries 44 conductor 50 leads to conductor 51, which leads to the terminal 45 of one end of the magnet coil 52 of bell 40. From the other terminal of the batteries 44 conductor 53 leads to conductor 166, which, extending to the left as viewed in Figure 4, is attached at 58 to the housing 11 with which lock bolt 15 is at all times in contact. To the right of conductor 53, conductor 166 leads to fixed terminal 164.

The electrical energy is thus transmitted to the bolt 15 and through the bolt to the conductor spring 57 carried by the bolt and which when in normal or bolt unlocked position bears against one end of a notch 59 in a contact plate 60, secured to the bolt 15 by two screws 63 which pass through insulating collars 65 and hold the plate to the bolt by means of the insulating washers 67 (Fig. 3). The insulating member 69 serves to keep the plate 60 out of electrical contact with the bolt.

A pin 72 (Figs. 4, 5, 7, 8), fixed in plate 60, has its outer end fixed to the slide member 84 of the double switch shown in detail in Figs. 7, 8 and 9. This switch includes three fixed slotted insulating members 88, 89 and 90 held together by hollow rivets 92, through which screws 93 pass securing the plates to the housing 11. To these plates are fastened two slotted metal guides 85 and 91 by rivets 97. The movable metal conductor slide 84 is held in place by guide 85 and the cooperating sliding member 99 is held in place by the guide 91. The sliding member 99 is located opposite sliding member 84, and is provided with a slot 102, through which passes pin 72. The three fixed insulating members 88, 89, 90 have slots 104, and the pin 72 passes through these slots also.

When the conductor 84 is moved completely forward (that is, to the left as viewed in Figs. 4, 7 and 8) by the movement of the pin 72, which will occur when the bolt 15 is in locked position, it is forced between the two points 103 and 105 of the terminal 110, which is fixed to the insulating member 88 and connected by a conductor 145

to the line 148 thus closing the circuit hereinafter described. The other sliding conductor 99 has the slotted hole 102, permitting the pin 72 to pass through it, so located that when the pin 72 is moved forward it will cause the conductor 99 to engage between the springs 116, 117 constituting terminal 120, which is secured to the insulating member 90 and connected to line 175 of the circuit hereinafter described, at the same time as the other conductor 84 contacts terminal 110. However, when the pin 72 moves back, that is, to the right as viewed in Figs. 4, 7 and 8, carrying the conductor 84 with it, and thereby immediately opening the circuit through terminal 116 and slide 84, the conductor 99 remains in place in contact with terminal 120 until the pin 72 travels to the other end of the slot 102, whereupon the pin 72 moves slide 99 enough to the right to break its contact with terminal 120, thus opening the circuit through that terminal and conductor slide 99. The conductor spring strip 125 passes through the fixed insulating members 88, 89, 90, and insures the flow of current between the traveling slides 84 and 99 in the closed position of Fig. 8.

There is provided a means for maintaining a normally open circuit between the leaf spring 57 and the plate 60, and for closing the circuit to set off the alarm when certain tampering operations are attempted. To this end, as here shown as an example, in the bolt 15 there is an axially movable pin 130 which operates lengthwise of the bolt, and which, when the bolt is in locked position, is forced back against coil spring 133 by a set screw 135 attached to the rear inside wall of the strike 26, so that the right hand end of the pin thrusts spring 57 out of contact with plate 60 and into the notch 59 thereof to open the alarm circuit. The set screw 135 is adjustable to vary the throw of conductor leaf spring 57 out of contact with plate 60; the less the throw, the less tampering movement of the door or bolt is necessary to close the circuit and sound the alarm when an unauthorized entry is attempted. For example, an attempt to insert an implement between the door and jamb would result in moving both door and bolt to the right, as viewed in Figs. 3, 4 and 5, away from set screw 135, whereupon the pin 130 is moved by coil spring 133 a corresponding distance to the left within bolt 15. As soon as the pin has moved whatever slight distance the device is set for, conductor leaf spring 57 returns to contact with plate 60 and closes the alarm circuit. The set screw 135 is preferably threaded into the keeper 26, and is locked in adjusted position by the lock nut 138.

The same result would occur if the jamb were cut away by some implement such as a chisel, and the bolt sawed through, for any such operation would break the thrust of pin 130 against conductor leaf spring 57 which holds it out of contact with plate 60.

The same result would occur if the door were to be removed from its hinges, for this would close the circuit through spring 57.

When an authorized person provided with the proper key moves the bolt 15 to locked position, spring 57 is moved by pin 130 to open circuit position. The double switch of Figs. 7 and 8 is so arranged that, immediately after spring 57 moves to open circuit position, conductor plate 70 84, moved by pin 72, closes the circuit through terminal 110.

The terminal 110 (Fig. 4) is connected by conductor 145 with conductor 148 which leads to one end of magnet coil 150, the other end of 75

which is connected by conductor 50 with the battery 44.

Upon any attempt to insert an implement between the door and jamb, or on any attempt to saw through the bolt 15, switch 57 closes the circuit from the bolt 15 to the plate 60, and causes the alarm to sound, the circuit being traceable as follows: from battery 44 through conductor 53, conductor 166 to bolt terminal 58, 5 through the bolt 15, spring 57, plate 60, pin 72, conductor plate 84 of the double throw switch to terminal 110 thereof; thence through conductor 145 and conductor 148 to magnet coil 150, thence through conductor 50 to the other terminal 15 of battery 44. This energizes the magnet coil 150.

Associated with the magnet coil 150 is a release mechanism which is actuated by energizing of magnet coil 150 to cause a closing of the alarm bell circuit. The release mechanism includes a bell crank lever rockable on a fixed pivot 155 and having the core arm 156 and the release arm 157, the latter being provided with the holding catch 158 and passing through a limited opening 159 in the spring switch 160. The spring switch 160 is connected by conductor 162 and with the terminal 163 of the bell circuit, and is normally held by catch 158 of the bell crank lever in open circuit position, that is, spaced away from its 20 other terminal 164, which is connected to one terminal of the battery 44, by conductors 166 and 53. The other terminal 45 of the bell circuit, leaving magnet coil 52, is connected to the other battery terminal by conductors 51 and 50. 25 The alarm bell and bell circuit may be of ordinary or usual construction and are so shown in the drawings.

The operation of the release mechanism is as follows: upon the energizing of coil 150, the core arm 156 of the release lever is moved about the fixed pivot 155, (clockwise, as viewed in Fig. 4) thereby causing catch 158 to release the spring switch 160, which thereupon springs to closed circuit position, thus closing the alarm bell circuit through spring switch terminal 164, and causing the alarm bell to sound as a result of the unauthorized attempted entry.

If the alarm has been set off, its circuit can be opened by depressing knob 170 of spring switch 160, which cams the holding catch arm 157 of the bell crank lever to the left, whereupon a leaf spring 172 causes it to hold the spring switch 160 in the open circuit position. The invention provides a construction however, such 55 that the knob 170 can be reached only by an authorized person.

The double throw switch of Fig. 4 is constructed to prevent sounding of the alarm when the bolt is moved to unlocked position by the proper key. It will be recalled that conductor plate 84 of the double throw switch did not contact terminal 110 until after spring 57 had been moved by pin 130 out of contact with plate 60. Consequently, the coil 150 of the release mechanism circuit was not energized, since the circuit was opened by spring 57 before it was closed at terminal 110. Upon movement of the bolt 15 toward unlocked position, the reverse action takes place, and the release mechanism circuit is opened at terminal 110 before it is closed by spring 57, the opening of the circuit at terminal 110 occurring upon initial movement of conductor plate 84 by pin 42. The alarm bell circuit is thus maintained open throughout normal

operation of the lock by a person using the proper key.

The invention includes means for causing the alarm to sound in the event the door is cut through for the purpose of unlocking the bolt by operating the bolt knob 14, and the knob is operated by an unauthorized person. This means is optionally settable by operation of a switch by an authorized person, the switch being accessible only to such a person.

This means includes the sliding member 99 of the double throw switch, above referred to, which contacts terminal 120 when the bolt reaches its maximum throw into locked position. The terminal 120 is connected by a conductor 175 to a 10 switch terminal 178 (Figs. 4, 5). The vertically movable plate 180 is normally forced upwardly by the coil spring 182, surrounding its lower end, the plate and spring being carried and guided within a housing 184 fixed to the lock casing 11. 15 Carried by the plate 180 is the terminal bridging member 186, having a finger actuated end 188 extending through a slot 189 in the lock casing 11. The plate 180 has a projecting lug 192, extending through the housing 184, by means of 20 which the plate 180 is held down against the action of its coil spring 182, with the bridging member 186 closing the circuit across switch terminals 178 and 193.

Fig. 12 shows the means for holding the bridging member 186 across the terminals when its finger actuated end 188 is depressed. Attached to the back plate 41 is a guide 197 in which slides the holding plate 199 provided at one end with the holding lug 201, which is movable with the 30 holding plate into and out of a position over the lug 192 on holding plate 180, in which position it holds down the bridging member 186 in contact with the terminals 178 and 193.

The holding lug 201 is formed with a beveled 40 upper edge cam 203, and is held in the right hand position of Fig. 12 by the leaf spring 205 which has one end fixed at 207 and its other end bearing against the holding plate 199 and urging it toward the right as viewed in Fig. 12. 45 When the plate 180 is depressed, its lug 192, bearing down on cam 203, forces the holding plate and lug 201 to the left as viewed in Fig. 12, and as soon as the lug 192 passes below the lug 201, spring 205 forces the lug to the right above 50 the lug 192 so that the lug 192 is held in lower position with the terminals 178 and 193 bridged by member 186 and the circuit closed across these terminals.

It will be noted that only the finger actuated 55 end 188 of the terminal bridging member 186 protrudes from the lock casing; and that when the circuit is thereby closed, the bridging member cannot be lifted to break the circuit, because of the holding mechanism just described, even 60 if such an attempt be made by an intruder cutting through the door.

The mechanism includes means for breaking this circuit when the bolt 15 is moved to unlocked position by operation of the lock with its proper 65 key, so that the optionally operable circuit closing mechanism will thereby be returned to normal inoperative, or open circuit, position.

For this purpose, the plate 199 pivotally carries the spring pressed lug 209, constantly urged into 70 the position of Fig. 12 by a spring 211 also carried by the plate 199. The lug 209 has an abutment edge 213 and a slip cam edge 215, and is located adjacent to and in the path of travel of a cam 219 carried by the cam disk 36 operated by 75

cylinder 30 above described. When the lock cylinder is operated by its proper key in a clockwise direction as viewed in Fig. 12 to move the bolt 15 to unlocked position, cam 219 contacts with the abutment edge 213 of pivoted lug 209, and forces it, with the plate 199 and holding lug 201 to the left, as viewed in Fig. 12, against the pressure of spring 205, thereby releasing plate 180, whereupon the plate 180 is forced upwardly by coil spring 182, carrying with it the bridging member 188 and thereby breaking the circuit across terminals 178 and 193.

If this circuit is closed by the bridging member, by depression of the finger end 188, before the locking operation, the cam 219 in its rotary movement simply slides over the slip cam edge 215 of lug 209, depressing it against the action of leaf spring 211, and having no effect on the circuit.

If the circuit is not closed across terminals 178 and 193 the action is the same, since the parts are normally maintained in the position of Fig. 12 whether this circuit has been closed or not.

The cam 219 makes one complete revolution in the locking operation, and one complete revolution in the opposite direction in the unlocking operation of the lock cylinder. If the circuit across terminals 178 and 193 has not been optionally closed, movement of the plate 199 to the left by cam 219, as viewed in Fig. 12, is merely an idle movement, as is its return movement to the right caused by spring 205 when the cam 219 has passed spring pressed pivoted lug 209.

By the means just described, when the circuit across terminals 178 and 193 has been optionally closed, this optionally operable circuit closing mechanism is always returned to normal open circuit position by the unlocking operation with the proper key. Moreover, the parts are proportioned and positioned so that the circuit is broken across terminals 178 and 193 by unlocking motion with the proper key before the bolt has moved far enough toward unlocked position for spring 57 to close the alarm circuit and cause sounding of the alarm. That is, the pin 31 and the cam 219 are located substantially at right angles to each other, so that before the pin 31 engages arm 16, the cam 219 will have engaged lug 209, which causes plate 199 to move back and release lug 192 before the bolt has moved more than a very short distance.

The invention provides means associated with the mechanism just described for closing another part of this circuit by the moving of the lock bolt 15 to closed position by its proper key from outside the door after the door is closed, and for keeping the circuit closed despite unlocking movement of knob 14 from within, so that even if an intruder cut through the door, he could not unlock it without sounding the alarm even if he should be able to reach and should actually turn knob 14 in the unlocking direction. The invention thereby provides alarm protection even against this manner of attempted entry, and the optionally operable mechanism may therefore be used by an apartment resident if he so desires whenever he is the last to leave. But opening of the door from outside by means of the proper key, however, breaks the alarm circuit across terminals 178 and 193, as already described, before spring 57 closes the alarm circuit.

Referring to this means (Figs. 4, 12 and 13), a switch 230 comprises a pair of spaced terminals 232 and 234 spaced apart and insulated from each other by an insulating mounting 235 secured to

the lock casing back plate 41 and insulated therefrom. Means for closing the circuit across these terminals includes the bridging contactor 236 carried by an insulator 238 secured to a slide 240 reciprocable in a casing 242 secured to the lock 5 casing back plate 41. The terminal 234 is provided with the binding post 248, from which a conductor 250 runs to the magnet coil 159 already described.

The terminal 232 is provided with the binding 10 post 252, connected by conductor 254 with terminal 193 of the optionally operable switch, whose cooperating terminal 178 is connected by the conductor 175 with switch 120 as already described. As viewed in Fig. 12, the left hand position of plate 240 closes the circuit through switch 230, and the right hand position thereof opens the circuit at said switch.

The sliding plate 240 pivotally carries a pair of opposed lugs 260 and 262. The lug 260 has an operating abutment edge 264 and an adjoining slip cam edge 266, and is normally maintained in the position of Fig. 12 by one arm 268 of a leaf spring 270 carried by the plate. The oppositely directed lug 262 has an operating abutment edge 25 272 and an adjoining slip cam edge 274, and is normally maintained in the position of Fig. 12 by the other arm 276 of the leaf spring 270.

Both lugs 260 and 262 lie in the path of the cam 219, by which the switch 230 is opened and closed. The parts are so arranged and proportioned that spring 57 opens the alarm circuit before switch 230 is closed, upon locking movement by the key, during which the cam 219 moves counterclockwise, as viewed in Fig. 12; 35 and upon the reverse or unlocking movement of said cam by the key the switch 230 is opened before the alarm circuit is closed by spring 57. Movement by the proper key, therefore, does not cause actuation of the alarm.

The switch 230 is closed by cam 219 which is operated by the proper key of the lock and slides over the slip cam edge 274 of lug 262, depressing the lug against spring 270, and then contacts the abutment edge 274 of lug 260 and moves plate 240 to the left causing contactor 236 to bridge the terminals 232 and 234. In the unlocking movement of cam 219 caused by the key, the cam slides over slip cam edge 266 of lug 260, depressing the lug against spring 270, and then contacts the abutment edge 272 of lug 262 and forces the lug and plate 240 to the right, thereby opening the switch 230.

By this time the bolt 15 has moved considerably toward completely unlocked position, at the 55 beginning of which movement the spring 57 moved to closed circuit position. The alarm was not operated, however, because the circuit was first opened between switch terminals 193 and 178 before spring 57 moved to closed circuit position, 60 as already described.

Since the pin 31 is operated only when the lock cylinder 30 is turned by the key, the foregoing mechanism, when operated by the key, will not cause the alarm to sound.

If, however, after the optionally operable safety mechanism has been set as above described, an attempt be made to move the bolt 15 to unlocked position by operating knob 14, the circuit will not be broken at switch 230, or across 70 terminals 178 and 193, since the lock cylinder will not be turned and the cam 219 will not move because the knob operation of the bolt 15 is independent of the key operation.

If the optionally operable safety mechanism 75

has been set as above described, and the door be cut through and the knob operated to unlock the door, the first unlocking movement of the bolt will close the alarm circuit at spring 57, and 5 since the rest of the circuit remains closed until key operated, the alarm will sound.

In such event, the actuating circuit through magnet coil 150 to close the alarm circuit is as follows: from battery 44, conductor 53, conductor 166 to casing 11 to bolt 15, through spring 57, plate 60 and pin 72 to slide 84, spring strip 125 to slotted conductor plate 99 (which plate remains in contact with the terminals of switch 120 and keeps this switch closed even though 10 initial knob movement of the bolt has opened switch 110), thence through switch 120, conductor 175, terminal 178, bridging member 186, terminal 193, conductor 254, switch 230 (which is opened and closed only by key movement of the 15 lock cylinder, and which was closed when the door was locked by the key from outside), thence by way of conductors 250 and 148 through magnet coil 150 to conductor 50 and thereby to the other battery terminal. Energizing of coil 150 causes sounding of the alarm through the closing of the alarm circuit already traced.

But key actuated unlocking movement of the bolt 15 will not cause the alarm to sound, for the circuit just traced will thereby be broken first 30 by the release of bridging member 186 caused by cam 219 acting on lug 209, and thereafter by the opening of switch 230 caused by cam 219 acting on lug 262. It will be noted that switch 230 is closed every time the door is locked by the 35 key, and opened every time the door is unlocked by the key; while holding plate 199, though it is given a circuit opening movement every time the door is unlocked by the key, is given no movement during locking by the key. The circuit opening movement of holding plate 199 is effective to open the circuit by releasing bridging member 186 only in the event the finger end 188 thereof has been depressed.

The invention provides means for giving access 45 to the interior of the lock casing to a person with the proper key and only to such person. For this purpose, the door 12 is provided on the lock casing 11, being hinged thereto at 282 and 284, and having the cylinder lock 286 by which 50 it is held closed and locked to the casing 14. The lock 286 may be operable by the same key that operates the bolt 15, or may be operable by a different key. Opening of the door 12 gives access to the interior of the lock casing 14 to replace the batteries 44, and to open the alarm circuit by depressing knob 170 of the spring switch 160. This construction prevents the stopping of the alarm by any one who has not 55 the proper key.

60 It has been pointed out how the optionally operable mechanism may be set to cause the alarm to sound by knob operation of the bolt from the inside of the door, for example, by any one cutting through the door in order to open it by reaching and turning the knob 14. It is to be noted that the lock casing is secured to the door by ordinary wood screws, so that any householder or apartment resident can affix the lock in place by a screw driver. It is to be noted that if the 65 door has been locked, any attempt at removal of the lock from the door by removing the screws 24 will cause the alarm to sound, for as soon as the lock is loosened, pin 130 will no longer hold the spring 57 in open circuit position, with the 70 result that it will move to closed circuit position 75

and cause the alarm to sound as soon as the lock is loosened whatever amount the pin 130 has been set for.

The invention provides safety release means for preventing the alarm from sounding when the door is open by preventing both knob and key operation of the bolt 15 when the door is open unless the safety release means is manually held in lock release position.

Referring particularly to Fig. 10, pivotally secured at 290 on the inside front face of lock casing 11 is a bell crank lever 292 having a cam arm 294 and a lock release arm 296. A leaf spring 300 has one end 302 secured to the bell crank lever, and its other or free end 304 bearing on the inner front face of the lock casing. The spring 300 urges the bell crank lever in a clockwise direction about its pivot 290, thereby causing the cam arm 294 to protrude slightly through an opening 306 provided for it in the lock casing 10 opposite the keeper 26. When the door is closed, cam arm 294 is cammed by the keeper 26 in a direction toward the back plate 41, which moves lock release arm 296 clear of a stop lug 308 on the under side of the bolt 15 (Fig. 5), which, in 15 the unlocked position of the bolt 15, occupies the dotted line position of Fig. 10. Thus, when the door is closed, the lock may be moved into and out of locked position by the knob 14 or its key. 20

When the door is open, however, spring 300 30 forces bell crank lever 292 in a clockwise direction until the cam arm 294 protrudes to its limit from the lock casing opening 306. This brings the lock release arm 296 into the path of the stop lug 308 on the bolt, and prevents movement of the bolt 35 into locked position.

The lock release means can be manually operated to permit moving the bolt to locked position when the door is open by depressing cam arm 294, to test the alarm, for example. Whenever the door is closed, the release means is automatically operated to free the bolt for locking movement by depression of the cam arm 294 by the keeper 26. It will be noted that whatever attempt be made, successfully or not, to manipulate the safety release means after the door has been locked, it will have no effect whatever upon the functioning of the alarm resulting from an attempted entry without the proper key.

From the foregoing description it will be seen 50 that the invention provides an alarm lock that can be applied to a door or other closure by screws and a screw driver; that can not be operated unintentionally when the door is open; and that functions to sound the alarm when entry is attempted in a number of ways without the proper key, including inserting a wedging instrument between door and jamb in an effort to force the bolt back, sawing through the bolt, actuating the bolt knob by cutting through the door to 55 reach it, unscrewing the bolt casing from the door, unscrewing the keeper, removing the door from its hinges, separating the lock casing from the strike by bursting open the door, and in any other way which results in movement of spring 60 57 to closed position except by using the proper key or by the bolt knob when it is not elected to use the optionally operable safety mechanism. Moreover, the circuit cannot be tampered with 65 because it is wholly contained in the lock casing and cannot be reached without the proper key, and the same is true of the alarm bell, the batteries, and all the mechanism of the invention which could otherwise be tampered with to 70 75

prevent the alarm signal from functioning in its intended way.

What I claim is:

1. An alarm lock for doors and the like, including a lock housing, a bolt member movable therein to locked and unlocked position, an alarm circuit in said housing, a source of current therefor, an audible alarm associated therewith in said housing and set in action by closing of said circuit, circuit closing means carried by said bolt member and movable to circuit closing position by unlocking movement of said bolt member, and means for opening said circuit before circuit closing movement of said bolt member comprising a key actuated switch in said circuit.
2. An alarm lock for doors and the like, including a lock housing, a bolt member movable therein to locked and unlocked position, an alarm circuit in said housing, a source of current therefor, an audible alarm associated therewith in said housing and set in action by closing of said circuit, circuit closing means carried by said bolt member and movable to circuit closing position by unlocking movement of said bolt member, and means for opening said circuit before circuit closing movement of said bolt member comprising a switch in said circuit and a bolt actuating knob and means associated therewith for controlling said switch.
3. An alarm lock for doors and the like, including a lock housing, a bolt member movable therein to locked and unlocked position, an alarm circuit in said housing, a source of current therefor, an audible alarm associated therewith in said housing and set in action by closing of said circuit, circuit closing means carried by said bolt member and movable to circuit closing position by unlocking movement of said bolt member, means for opening said circuit before circuit closing movement of said bolt member comprising a key actuated switch in said circuit and a key controlled housing closure for said lock housing.
4. An alarm lock for doors and the like comprising a lock housing having a key controlled closure, and, within said housing, an audible alarm, an alarm circuit for actuating said alarm when said circuit is closed, a source of current therefor, a normally open switch in said alarm circuit, means for closing said switch including a control circuit, a bolt member movable to locked and unlocked position, key controlled means for moving said bolt, knob controlled means for moving said bolt, means for opening said control circuit after the bolt has moved into locked position and before completion of its locking movement comprising a bolt actuated switch in said control circuit movable to circuit closing position at the beginning of bolt unlocking movement, and switch mechanism in said control circuit movable to closed circuit position by said key controlled means and said knob controlled means upon opening of said control circuit by said bolt actuated switch and movable to open circuit position by said key controlled means and said knob controlled means prior to closing of said circuit by the bolt actuated switch at the beginning of bolt unlocking movement.
5. An alarm lock for doors and the like comprising a lock housing having a key controlled closure, and, within said housing, an audible alarm, an alarm circuit for actuating said alarm when said circuit is closed, a source of current therefor, a normally open switch in said alarm circuit, means for closing said switch including a control circuit, a bolt member movable to locked and

unlocked position, key controlled means for moving said bolt, knob controlled means for moving said bolt, means for opening said control circuit after the bolt has moved into locked position and before completion of its locking movement comprising a bolt actuated switch in said control circuit movable to circuit closing position at the beginning of bolt unlocking movement, switch mechanism in said control circuit movable to closed circuit position by said key controlled means and by said knob controlled means upon opening of said control circuit by said bolt actuated switch and movable to open circuit position by said key controlled means and by said knob controlled means prior to closing of said circuit by the bolt actuated switch at the beginning of bolt unlocking movement, and means to prevent said knob controlled means from so moving said switch mechanism to open circuit position comprising optionally settable switch holding mechanism released by key operation of the bolt.

6. Alarm lock mechanism for doors and the like including a keeper, a variably positionable regulator associated therewith, a lock housing and, within said lock housing, an audible alarm, circuit means for operating said alarm, a source of current therefor a bolt movable to locked and unlocked positions, key controlled means for moving said bolt, knob controlled means for moving said bolt, a bolt controlled switch in said circuit means having spring means normally urging it toward closed position, a switch opener carried by the bolt and movable to switch opening position by contact with said variably positionable regulator on completion of bolt movement into locked position, and switch means in said circuit means opened by said key controlled means and by said knob controlled means by bolt unlocking movement thereof and closed by bolt locking movement thereof.

7. Alarm lock mechanism for doors and the like including a keeper, a variably positionable regulator associated therewith, a lock housing and, within said lock housing, an audible alarm, circuit means for operating said alarm, a source of current therefor, a bolt movable to locked and unlocked positions, key controlled means for moving said bolt, knob controlled means for moving said bolt, a bolt controlled switch in said circuit means having spring means normally urging it toward closed position, a switch opener carried by the bolt and movable to switch opening position by contact with said variably positionable regulator on completion of bolt movement into locked position, switch means in said circuit means opened by said key controlled means and by said knob controlled means by bolt unlocking movement thereof and closed by bolt locking movement thereof, a key lockable closure for said lock housing, and a manually operable switch in said circuit means accessible by key opening of the housing closure.

8. Alarm lock mechanism for doors and the like including a lock housing having therein a bolt, an electrically operable audible alarm and circuit means including a current source therefor, a keeper for said bolt, means associated therewith providing a switch movement regulator, a switch in said circuit means movable to circuit closing alarm operating position by relative movement of said switch and said regulator toward each other and by relative movement of said bolt and regulator away from each other, a bolt carried switch opener cooperable with said

switch and said regulator, key controlled means and knob means for actuating the bolt, and means for preventing operation of the alarm during normal operation of the lock comprising key controlled and knob controlled switch mechanism in said circuit means.

9. Alarm lock mechanism for doors and the like including a lock housing having therein a bolt, an electrically operable audible alarm and circuit means therefor, a keeper for said bolt means associated therewith providing a switch movement regulator, a switch in said circuit means movable to circuit closing alarm operating position by relative movement of said switch and said 15 regulator toward each other and by relative movement of said bolt and regulator away from

each other, a bolt carried switch opener cooperable with said switch and said regulator, key controlled means and knob means for actuating the bolt, means for preventing operation of the alarm during normal operation of the lock comprising key controlled and knob controlled switch mechanism in said circuit means, and optionally settable means for causing operation of the alarm by bolt unlocking movement of said knob means comprising manually settable switch 10 closer associated with said circuit means and movable to un-set or switch opening position upon bolt unlocking movement of said key controlled means.

JOSEPH R. RODTH. 15
